CONTAINER

John F. Peters, Leonia, N. J., assignor to American Can Company, New York, N. Y., a corporation of New Jersey

Application July 30, 1932, Serial No. 626,278

4 Claims. (Cl. 220—39)

The present invention relates to containers having removable covers which are applied by a turning movement, container and cover being provided with interrupted threads for securing 5 the cover in container closing position, provision being made for preventing the accidental loosening or dislodgment of the cover.

An important object of the present invention is the provision of a container and cover provided 10 with screw threads for tightly holding the cover into container closing position and having locking elements associated with one of the threaded parts for preventing accidental loosening of the cover.

15 Numerous other objects and advantages of the invention will be apparent as it is better understood from the following description, which, taken in connection with the accompanying drawing, discloses a preferred embodiment 20 thereof.

Referring to the drawing:

Figure 1 illustrates one embodiment of the invention being a front elevation of a container and its applied cover;

25 Fig. 2 is a view similar to Fig. 1, illustrating container and cover in separated position;

Fig. 3 is an enlarged sectional view taken substantially along the line 3—3 in Fig. 1 and illustrating the cover in sealing position upon the 30 container;

Fig. 4 is a fragmentary plan sectional detail taken substantially at a position indicated on the container by the line 4—4 in Fig. 2 and illustrating parts of the cover and container during 35 application of the cover and before it is moved into container closing position; and

Fig. 5 is a view similar to Fig. 3 and illustrating the position of the cover upon the container as it is being moved into closing position.

40 The present invention is particularly directed to an improved locking feature for a threaded container or can which holds the can cover in can closing position so that it cannot be accidentally loosened or displaced but may be easily unscrewed and the can opened when desired.

Short thread sections are struck out or formed in the adjacent walls of can and cover and provide for drawing the cover downwardly into tight sealing position as the same is turned relative to the can.

50 The threads of the can body are preferably spaced apart circumferentially a distance greater than the longitudinal dimension of a can cover thread section. This is to permit the latter threads to pass freely downwardly between the body thread sections by

straight axial movement of the cover relative to the can and prior to any relative turning movement to lock the cover in position.

Each of the thread sections of the can, according to the embodiment of the invention as herein disclosed, is formed with a lateral projection or abutment. Each projection cooperates with the corresponding thread section of the cover during its application to the can to snap by the end of the cover thread and to present a barrier or stop 10 to hold the cover against inadvertent removal. Reverse movement of the cover is resisted by these lateral locking projections of the can threads but is easily overcome by force when the cover is unscrewed at which time the parts again 15 spring out and unsnap while the thread sections are disengaged.

Such a can comprises a metal container body 11, provided with a bottom or end member 12 which may be secured in any suitable manner as 20 by a double seam. The upper end of the body is open and is strengthened by an encircling bead 13 struck out from the metal and projecting beyond the wall of the can body. Above the bead 13 a vertical shoulder part 14 is preferably provided (Figs. 2, 3 and 5) and above this shoulder, an upper wall part 15 extends.

The top of the wall 15 is preferably bent inwardly to provide a curled upper edge 16 which forms a smooth mouth for the open end of the 30 can and further reinforces or strengthens this part of the can body. This can is adapted to be closed by a cover member 21 which may be formed with a top wall 22 and a depending side wall or flange 23. A suitable knurling 24 is de- 35 sirable and is formed in the flange wall to permit a more secure grasping of the cover when it is being turned in closing the can.

The outer edge of the cover wall 22 is also formed with an annular depressed bead 25 which 40 is adapted to engage against the curled edge 16 of the can when the cover is in closing position. Threaded elements are formed in both can and cover for this purpose and these cooperate to draw the beaded section 25 inside and on top of the 45 curled body edge 16 as shown in Fig. 3.

The threaded connection comprises an interrupted or relatively short thread section 28 struck outwardly from the can wall part 15, this thread section being disposed at an angle to the horizontal. A corresponding inclined thread section 29 is forced inwardly as an integral part of the cover flange 23. This general form of thread is often used in tin cans for securing can and cover together.

The thread sections 28, 29 are out of vertical alignment when the cover 21 is first applied and are brought into cooperative position by a turning or rotation of the cover relative to the can. This turning movement brings the cover threads 29 beneath the body threads 28 and the inclined position of the threads causes the cover to be drawn down upon the can into container closing position.

Downwardly extending lateral projections or abutments 31 are arranged at or near the forward or upper end of each threaded section 28. When the cover is first positioned its threaded sections 29 are arranged to the right (viewing Fig. 2) of their companion threaded sections 28 and downwardly extending projections 31. The body thread sections 28 are preferably circumferentially spaced apart a distance greater than the longitudinal dimension of each cover thread 29 to permit the latter to pass downwardly between the body threads in the first movement of applying the cover. As the cover is rotated to bring the threaded sections into engagement the threaded sections 29 of the cover ride over the projections 31, the flange of the cover being sprung outwardly in the movement sufficiently to permit this relative movement, as illustrated in Figs. 4 and 5.

The cover is rotated relatively to the can until the thread sections 29 have passed beyond the lateral extension 31 when the cover flange springs back into its normal shape (Fig. 3). Thereafter slight further rotation of the cover upon the body causes the cover to be drawn tightly down upon the curl 16. The lateral projections 31 are now behind the threads 29, as illustrated in dotted lines in Fig. 4.

The cover cannot be accidentally removed from its container closing position without reversing the springing process on the cover flange and without causing the thread sections 29 to again move over the lateral thread extensions 31. This reverse movement, however, can be easily brought about when the cover is forcibly turned in the opening operation.

It is thought that the invention and many of its attendant advantages will be understood from the foregoing description and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container, comprising a body having an open end, a cover having a flange fitting over said open end, thread sections formed in said body adjacent its open end, thread sections formed in said cover flange and adapted to engage with the body threads when said cover is applied and ro-

tated relative to said body to close the container, and lateral projections associated with one of said thread sections and adapted to spring outwardly and snap behind the other of said thread sections during the application of the cover to lock it in container closing position and prevent accidental loosening, said body having a vertical shoulder part which enters within the cover flange and holds the flange spaced from the body for the said operation of said projections and cover thread sec- 10

15 2. A container, comprising a body having an open end and an upper curled edge surrounding the opening, a cover for closing said opening and having a depending flange extending down along- side of and spaced outward from said body when said cover is applied and also having an annular bead for engaging said curled body edge, thread sections struck outwardly from the wall of said body adjacent its curled edge, thread section: 20 struck inwardly from the flange of said cover and adapted to engage with said body threads when said cover is rotated relative to said container body, and projections extending downwardly from the upper end of the thread sections of the body 25 and locking with the thread sections of the cover to hold the cover in closing position and to prevent its accidental loosening, said thread sections being relatively short and the thread sections of the cover being adapted to pass directly downward 30 between the thread sections of the body.

3. A container, comprising a body having an open end, a cover fitting over said open end and having a depending flange provided with circum- 35 ferentially spaced inclined thread sections, said body adjacent its open end having inclined thread sections circumferentially spaced apart a distance greater than the longitudinal dimension of a said cover thread section, said body threads each having a downwardly disposed projection at the upper 40 end thereof adapted to engage a thread section of the cover when applied to yieldably resist ac- cidental loosening of the cover.

4. A container, comprising a body having an open end, a cover fitting over said open end and 45 having a depending flange provided with circum- ferentially spaced inclined thread sections, said body adjacent its open end having inclined thread sections circumferentially spaced apart a distance greater than the longitudinal dimension 50 of a said cover thread section, and an abutment on said body disposed in circumferential alignment with one of said cover threads and over which said cover thread yieldably passes when the cover is applied, said abutment engaging the upper end of said cover thread when said cover is applied to yieldably resist reverse displacement of said cover relative to said body.

JOHN F. PETERS.
